BAR STOCK AND REINFORCING BAR

Odd Wennerberg, Manhasset, and Joseph D. Stites,
New York, N. Y., assignors to Wegner Machinery Corporation, Long Island City, N. Y., a corporation of New York

Application September 8, 1945, Serial No. 615,225

7 Claims. (Cl. 72—111)

1

This invention relates to reinforcing bars for use in concrete structures and the like, and particularly to that type of bar which comprises two rod-like sections joined in substantially parallel alignment by an integral intermediate section, or web, of lesser cross-sectional area than either of said rod-like sections, which type of bar is twisted around its longitudinal axis before use to form in effect a helical structure comprising two helices having a common axis. The use and purpose of such bar and the reasons for twisting the same are all well known, and it is likewise well known to provide on this type of bar ribs arranged on the outer surfaces of the bar, usually transversely, diagonally or spirally, herein called "transverse ribs," for the express purpose of increasing the strength of the bond between the bar and the concrete or like material in which it is set or contained.

An object of this invention is to provide a bar stock of the above type which, when twisted and used as a reinforcing element, forms with the concrete or similar substance in which it is set a bond of great strength.

A further object of the invention is to provide a twisted reinforcing bar of the described type having ribs so shaped as to promote between the bar and the concrete a lasting bond of such strength as will successfully resist the stresses arising in reinforced concrete structures.

Other objects and advantages will be apparent from the following description of the invention with respect to the specific embodiments thereof which are illustrated in the attached drawing:

In the drawing:

Fig. 1 is a plan view of a bar stock, before the twisting operation, embodying the principles of this invention;

Fig. 2 is a view of the same bar at right angles to the view shown in Fig. 1;

Fig. 3 is a plan view of the same bar after twisting, said bar being thus ready to be used as a reinforcing element;

Fig. 4 is a cross-sectional view of the untwisted bar stock shown in Figs. 1 and 2, taken at 4—4 as indicated;

Fig. 5 is a plan view of another bar embodying the principles of this invention;

Fig. 6 is a side view of yet another bar embodying the principles of this invention;

Fig. 7 is a cross-sectional view of the untwisted bar stock shown in Fig. 5, taken at 7—7 as indicated;

Fig. 8 is a cross-sectional view of the untwisted bar stock shown in Fig. 6, taken at 8—8 as indicated;

Figs. 9, 10 and 11 are cross-sectional views of other untwisted bar stock shaped in accordance with this invention.

Referring to the drawings, the bar shown in Figs. 1 to 4, inclusive, embodies in particular form the basic elements representative of the type of bar, above described, which has been used or proposed for use as a reinforcing element in concrete or like structures. The bar comprises the two rod-like sections 15 which are joined in substantially parallel alignment by the intermediate section, or web, 16. This web has a cross-sectional area which is less than that of either of the rod-like sections. The rod-like sections are usually roughly, or approximately, circular in cross section, by which is meant that they are circular, elliptical or ovate in shape, the exact shape forming no part of this invention and varying somewhat according to the specific method of manufacture, which is usually some type of rolling process. The web 16 may bear the proportion shown in the drawing to the rod-like sections 15, or it may be thicker or wider, its specific shape and size being no part of the present invention. It will be noted that the general shape formed by the web section and the two rod-like sections is roughly that of a dumbbell, and many different and specific shapes of this dumbbell form have been shown and described in the art. Running along the outer surface of each rod-like section 15 and longitudinally thereof is the longitudinal rib 17. It is usually present in reinforcing bars of the type here under discussion because the manufacture of the bar by rolling is simplified if a certain amount of metal, as represented by the longitudinal rib 17, is provided between the mill rolls during the bar shaping operation.

The advantages and benefits of the present invention derive from the shape of the transverse ribs disposed on the bar. We have discovered that if the transverse ribs (such as the ribs 18 in Figs. 1 to 4, inclusive), have peripheral surfaces which define an angular peripheral outline, i. e., the edges of the rib outlining an angular projection so that the depth of the rib as measured from the surface of the rod-like section to the rib edge reaches a maximum at a point which roughly forms the apex of an angle defined by the rib edges and represents a point of maximum rib depth, the bonding characteristics of the twisted bar will be materially improved and enhanced. In the preferred form of the invention each rib is roughly, or approximately, triangular in peripheral outline or has sections of its extending surface in that form. The form taken by the ribs

18 of the bar shown in Figs. 1 to 4, inclusive, if preferred, but the benefits of the invention may be obtained by the provision of ribs of equivalent shape. Another desirable form is shown in Fig. 9, where the ribs 30 are so shaped as to form two projecting angles 31, thereby providing, in effect, two triangular shaped wings or lugs projecting from the same surface of the rod-like section of the bar. The form shown in Fig. 4 is, however, preferred and when used, the rib 18 is preferably so located that the apex of its outwardly extending angle lies above the outer, i. e. web-free, surface of the section 15. However, good results will be obtained if the rib is so formed that the apex of its projecting angle lies outwardly of the inner surface of the section, as illustrated in Fig. 10 by the location of ribs 25 with respect to the section 24, or lies in intermediate positions, as illustrated in Fig. 11 by the location of ribs 27 in the section 26. However, in these forms the bonding strength is not as great.

The ribs to which reference is thus made are, from a manufacturing standpoint, best located in planes at right angles to the longitudinal axis A of the bar, but they may be diagonally disposed without materially affecting the bonding properties of the final twisted bar.

The spacing of the ribs with respect to the longitudinal axis of the bar and with relation to each other is dictated by known considerations as to bonding strength, strength of the bar, etc. In the preferred form shown in Figs. 1 to 4, inclusive, a transverse rib 18 is located on each side of each rod-like section 15 so that at intervals along the bar a plane at right angles to the longitudinal axis will pass through four of the ribs 18. However, if desired, the ribs may be staggered in various ways, such as shown in Figs. 5 and 7, where the ribs 28 formed on each of the rod-like sections 29 are staggered so that no plane taken at right angles to the longitudinal axis of the bar contains more than two ribs, those ribs being ribs on opposite sides of the same rod-like section 29. Again, by way of example, the ribs may be staggered as indicated in Figs. 6 and 8, where ribs 22, which occur on either side of the rod-like sections 23, are staggered with respect to each other so that the ribs on the same sides of the sections 23 will fall in the same plane.

In the preferred form of bars embodying the principles of this invention the ribs formed on the rod-like sections of the bar do not extend across the intermediate web which connects those sections in parallel alignment, i. e., the surface of the integral web is uninterrupted by ribs. For example, in the form shown in Figs. 1 to 4, inclusive, the rib 18 merges into the surface of the rod-like section 15 short of or at the point or area where the surface of the web 16 merges into that of the rod-like section. The advantage of this arrangement is best described by comparison with the arrangement shown in Figs. 6 and 8 where the rib 22 extends entirely around the bar but is shaped, in accordance with this invention, to form the projecting angular wings or lugs 33. There the rib extends over the web 34, and it will be observed that if the bar is twisted, the rib will form a pocket with the web. These pockets formed by the passage of the rib 22 over the web 34 may trap moisture or air as the concrete rises around the bar, thereby preventing a concrete-metal contact and diminishing bonding strength and also providing a place where corrosion of the bar due to trapped air and moisture may readily take place. In the preferred form of the inven-

tion, as shown in Figs. 1 to 4, inclusive (and also in the forms illustrated by Figs. 5, 7, 9, 10 and 11), the use of ribs which do not extend across the intermediate portion or web of the bar prevents the formation of such a pocket when the bar is twisted.

The reference to specific forms and shapes in the foregoing description has been by way of example and with no intention of excluding such equivalents as fall within the intent and spirit of the invention and the language of the appended claims.

We claim:

1. A bar adapted to be twisted around its longitudinal axis to form a reinforcing element, said bar comprising two elongated rod-like sections joined in substantially parallel alignment by an integral web of cross-sectional area less than the cross-sectional area of either of said rod-like sections and integral ribs transversely spaced at intervals on the surface of said bar, said ribs being roughly angular in cutline and having a point of maximum rib depth located over the outside surface of said rod-like section.

2. A bar adapted to be twisted around its longitudinal axis to form a reinforcing element, said bar comprising two elongate rod-like sections joined in substantially parallel alignment by an integral web of cross-sectional area less than the cross-sectional area of either of said rod-like sections and outwardly extending integral ribs transversely spaced at intervals on the surface of said bar, the extending sections of said ribs being roughly triangular in peripheral outline.

3. A bar adapted to be twisted around its longitudinal axis to form a reinforcing element, said bar comprising two elongate rod-like sections joined in substantially parallel alignment by an integral web of cross-sectional area less than the cross-sectional area of either of said rod-like sections and outwardly extending integral ribs transversely spaced at intervals on the surface of said bar, said ribs being approximately triangular in peripheral outline.

4. A bar adapted to be twisted around its longitudinal axis to form a reinforcing element, said bar comprising two elongate rod-like sections joined in substantially parallel alignment by an integral web of cross-sectional area less than the cross-sectional area of either of said rod-like sections and outwardly extending integral ribs transversely spaced at intervals on the surface of said bar, said ribs being approximately angular in peripheral outline, the apex of the projecting angle of said rib lying over the outside surface of said rod-like section.

5. A bar adapted to be twisted around its longitudinal axis to form a reinforcing element, said bar comprising two elongate rod-like sections joined in substantially parallel alignment by an integral web of cross-sectional area less than the cross-sectional area of either of said rod-like sections and outwardly extending integral ribs transversely spaced at intervals on the surface of said bar, said ribs being approximately angular in peripheral outline and the surface of said integral web being uninterrupted by said ribs.

6. A twisted reinforcing bar comprising two elongate rod-like sections longitudinally joined by an integral web, said bar being twisted about its longitudinal axis into a helical structure comprising two helices having a common axis and a series of transverse ribs spaced longitudinally.

of said bar and integral therewith, said ribs being approximately angular in peripheral outline.

7. A twisted reinforcing bar comprising two elongate rod-like sections longitudinally joined by an integral web, said bar being twisted about its longitudinal axis into a helical structure comprising two helices having a common axis and a series of transverse ribs spaced longitudinally of said bar and integral therewith, said ribs being approximately triangular in peripheral outline and the surface of said integral web being uninterrupted by said ribs.
